United States Patent Office

Des. 207,759
Patented May 23, 1967

207,759

RESUSCITATOR

Mary D. James, 234 S. Carondelet Ave.,
Los Angeles, Calif. 90057

Filed Apr. 4, 1966, Ser. No. 1,757

Term of patent 7 years

(Cl. D83—1)

FIG. 1

FIG. 2

FIG. 4

FIG. 1 is a plan view of a resuscitator embodying my new design.

FIG. 2 is a side elevational view thereof.

FIG. 3 is a fragmentary sectional view along the line 3—3 in FIG. 1.

FIG. 4 is a fragmentary sectional view along the line 4—4 in FIG. 1.

I claim:

The ornamental design for a resuscitator, substantially as shown.
